(12) **United States Design Patent** (10) **Patent No.:** **US D1,023,157 S**
(45) **Date of Patent:** **** Apr. 16, 2024**

(54) **GAMING MACHINE**

(71) Applicant: **Aristocrat Technologies, Inc. (ATI)**,
Las Vegas, NV (US)

(72) Inventor: **Steven Santisi**, Las Vegas, NV (US)

(73) Assignee: **ARISTOCRAT TECHNOLOGIES,
INC. (ATI)**, Las Vegas, NV (US)

(**) Term: **15 Years**

(21) Appl. No.: **29/758,498**

(22) Filed: **Nov. 16, 2020**

(51) LOC (14) Cl. **21-03**

(52) U.S. Cl.
